MACHINE FOR FORMING PERFORATED BLANKS

Filed Sept. 18, 1928 3 Sheets-Sheet 3

UNITED STATES PATENT OFFICE

ABRAHAM NOVICK, OF FLUSHING, NEW YORK, ASSIGNOR TO F. L. SMITH THE MACHINE CO., INC., OF NEW YORK, N. Y., A CORPORATION OF NEW YORK

MACHINE FOR FORMING PERFORATED BLANKS

Application filed September 18, 1928. Serial No. 306,733.

This invention relates to punch presses and is in the nature of improvements which may be used with the machine illustrated in my application, Serial No. 256568 filed February 24th, 1928 in which I provide a magazine to receive the punching from the press; the magazine extending downwardly from the dies and then curving forwardly into an upward extension from which the blanks 5 may readily be removed in packs or bundles without interrupting the operation of the machine.

In the machine of the present invention envelope fasteners, in the form of fibre buttons, are formed. It has been found in practice that occasionally these buttons jam in the curved part of the magazine, which, unless otherwise provided for, causes serious damage to the machine.

An object of the present invention is to guard against injury to the machine in case one or more of the magazines becomes stopped. To this end the magazines of the illustrative machine are secured to a support which is pivotally mounted on the machine frame and yieldingly held in position to maintain the receiving end of the magazine normally against the lower end of the die. I have shown a plurality of magazines and when one of them becomes jammed the continuous feeding of the fasteners causes the magazines to swing away from the dies, the upward extensions of the magazines swinging from a vertical position to an inclined position which indicates to the operative that the passage in one of the magazines has become obstructed.

A feature of the invention relates to means to facilitate the separation of the fasteners into packs and the removal of the packs from the magazine.

Other objects and advantages will herein-after appear.

In the drawings forming part of this specification.

Figure 1 is a sectional side view of a punch press showing my invention applied thereto.

Figure 2 illustrates the various punches and plungers used in the machine.

Figure 3 is a top plan view of the machine with some of the parts removed.

Figure 4 is a view of one of the fasteners or buttons.

Figure 5 is a detail sectional view showing the relation of one of the dies and its associated magazine.

Figure 6 is a detail, sectional elevation showing the magazine swung to an abnormal position due to the obstruction of the fasteners therein.

Figure 7 is a top plan view of a strip of material which has been partly fed thru the machine.

Figure 8 is a detail sectional elevation of one of the magazines showing the separating tool before its application.

Figure 9 is a view similar to Figure 8 but shows a pile of fasteners separated from the others and the lower end of the assembly wire bent by the tool.

Figure 10 is a top plan view of a portion of the machine including the punch and die sets.

Figure 11 is a detail top plan view illustrating the operation of the separating tool or plate.

Figure 12 is a detail front elevation illustrating the manner of detachably supporting the magazines.

The invention is herein shown as applied to a punch press for making envelope fasteners 15 of the button type provided with perforations 16 to facilitate securing to envelopes by the usual eyelets.

The machine includes a main frame 17 supporting a bed plate 18 upon which are mounted punch and die sets 20 which may be operated to act upon a strip 21 of suitable material to punch out the buttons 15, thus leaving holes 21A (Figure 21) in the strip. The punch and die sets are operated by a plunger 22 mounted on a slide 23 suitably guided on the main frame. To operate the plunger 22 there is provided a power driven shaft 24 rotatably supported in the main frame and provided with a fly wheel 25. The shaft 24 is provided with a crank pin 26 co-operating with a connecting rod 27 attached to the plunger 22 at 28.

Each punch and die set 20 includes a punch 30 which co-operates with a die 31. The punches are guided in a punch block 32 and the dies are carried in a plate 33 to which the die block 32 may be secured by screws 34 to form a unit which may be secured to the bed plate 18 by screws 35. The die plate 33 has a depression therein to form, with the die block 32, a slot 36 thru which the strip 10 of material 21 is conducted; said strip being guided in any simple manner and being fed intermittently in a manner well known in the art to expose fresh portions thereof to the action of the punch and die sets.

15 To return the punches 30 to their normal positions, clear of the strip of material, after each punching operation, there is provided a return plate 40 which is pressed upwardly by the springs 41 supported into holes 20 42 formed in the die block 32. Each punch 30 is provided with a head 43 which rests upon the plate 40 so that the punches may be carried upwardly with the plate by the action of the springs 41. The plate 40 may be arrested in its upper position by headed studs 25 44 secured to the die block 32.

The strip of material is fed from the left to the right of the machine in the direction of the arrow (Figure 7) and before it reaches the punch and die sets 20 it is acted upon by perforating punches 47 (Figures 2 and 10). Said punches co-operate with dies 48 (Figure 3) in the die plate 33 and are effective to form the hole 49 which later become the holes 16 in button 15. Plungers 50 (Figure 10) are provided to enter the previously formed perforation 49 to align the perforated portion of the strip of material with reference to the punch and die set 20; the plungers entering holes 50A in the die block 33 (Figure 3). This aligning is done prior to the action of the punches 30 to stamp out the buttons 15. Each punch 30 is provided with a projection 52 and all of the projection 52 enter the perforations 49 to further assist in aligning the strip 21 with reference to the punches 30.

The punches 47 and the plungers 50 are provided with heads 53 and 54 respectively to engage the return plate 40 so as to be restored thereby to normal with the punches 30.

The punchings 15 are received by downwardly extending portions 56 of magazines 57, said portions being connected by curved portions 58 with delivery portions 59 extending vertically upward at the front of the machine and from which the punchings may readily be removed in packs or bundles in a manner hereinafter described. The magazines 57 are in the form of tubes and the delivery sections 59 are open at the top and are provided at the front with slots 60, (Figures 3, 8, 9 and 11), to facilitate the insertion of a tool 61, hereinafter described, for the pur-

pose of separating the buttons into bundles for removal from the magazine.

To prevent injury to any one of the magazines, which would otherwise occur when a magazine becomes clogged, all are carried by a support 65 including two ears 66 pivotally supported by a shaft 67 carried by brackets secured to a table or forward extension 69 which may be secured to the bed plate 18 by screws 70. A spring 71 is connected at one end to the table 69 and its other end to a bracket 72 secured to the support 65 to hold said support in its normal position against studs 73 projecting from the side of the extensions 69 and thru slots 74 in the ears 66. While the stamping of the buttons continues after one of the magazines becomes jammed the piling up of the buttons at the receiving portion 56 of the magazine against the action of the spring 71 swings the magazines from their normal positions to inclined positions, illustrated in Figure 6, which indicates to the operative that one of the magazines is clogged.

To facilitate the removal of the jammed magazine so that it may be unstopped, each magazine is detachably mounted on the support 65 by a clamp block 77 which has a depression 78 to fit around or embrace the magazine which is cylindrical in cross-section; each clamp 77 is secured to the support 65 by screws 79.

To hold the portions 56 of the magazine in alignment with the dies 31, to insure unobstructed passage of the buttons from the dies to the magazines, there is provided a plate 80 secured to the lower face of the die plate 33 in any suitable manner; the plate 80 being provided with holes 81 (Figure 5) in which the portions 56 engaged to register with said dies.

It will be understood that the punchings 15 as they are formed, fit tightly in the upper part of the dies 31. This assists in preventing retrograde movement of the buttons in the magazine, which the weight of the column of punchings in the delivery portion 59 tends to produce. The hole 82 in the die flares at 83 so as to facilitate free passage of the punchings from the die to the magazine.

By an inspection of Figure 3 it will be seen that the dies 31 are arranged in two rows extending fore-and-aft of the machine, or in other words transversely of the strip of material 21, and to reduce the waste of the material to a minimum, the dies of one row are offset with reference to the dies of the other row. The receiving portions 56 of the magazines are accordingly arranged in two rows and the curved portion 58 of the said magazines, as they reach forward extend outwardly from each other to the delivery portions 59; the portions 59 being arranged in a single row extending transversely of the machine or, in other words, at right angles 120 to the direction of the strip 21.

to the rows in which magazine portions 56 are disposed. It will also be understood that the curved portions 52 of the two rows of magazines extend in opposite directions and in fan-like relation to the single row of delivery portions 59.

To separate the buttons or fasteners 15 into bundles or stacks preparatory to their removal from the magazines, a tool 61, in the form of a flat plate and adapted to act upon the stacks simultaneously is provided. Said plate has projections 85 (Figures 8, 9, 11) to enter the slots 60 in the magazines, the projections 85 being pointed so that they may readily be forced between the fasteners contained in the magazines. Before the tool 61 is pushed into the magazines wires or rods 87 are inserted through the perforations 15 of the pile of fasteners, the upper end 88 of each wire being bent to engage the upper end of the magazine to support the wire so that the lower end of each extends beyond the position or station at which the tool 51 is applied. The extensions 85 are provided with hooks 90 which, when the tool 61 is inserted, engage behind the wires 87. After the wires have been embraced by the hooks 90 the pile of fasteners in the various magazines may be raised by the tool 61 to separate them from the other fasteners in the magazine. The ends of the wires 87 may then be bent outwardly by tilting the tool 61 as in Figure 9. After the lower ends of the wires have been so bent the tool 61 may be removed subsequent to which the bundles of fasteners may be removed from the magazines individually and the freshly bent end of each wire 87 may then be further bent by means of a pair of pliers, or any other suitable tool, to retain the fastener in a pile on said wire.

To assist in inserting the tool 61 into the magazines there are provided two forwardly extending bars 93 secured to the plates 66; said bars 92 serving as guides upon which the tool may be slid into the magazines. To assist in locating the tool 61 laterally, with reference to the magazines, the left hand end of the tool 61 is placed against the left hand side plate 66 which extends above the latter at 94 as shown in Figure 1.

To assist in gauging the number of fasteners in each pile or in other words to indicate when the tool 61 should be used, there may be provided one or more indicators 95 near the upper ends of the magazines which may be located a distance above the bars 93 corresponding to the total height of a predetermined number of fasteners. It will be understood that other indicating means, such as a counter, suitably connected to and operated by the machine may be used to inform the operative when a predetermined number of fasteners have advanced in the deliv-

ery end of the magazine beyond the position at which the tool 61 is inserted.

While I have illustrated and described in detail the preferred form of my invention it will be understood that changes may be made therein and the invention embodied in other structures, I do not therefore desire to limit myself to the specific construction illustrated but intend to cover my invention broadly in whatever form its principles may be utilized.

What I claim is—

1. In a machine of the class described the combination of punching means, a magazine, said magazine including a receiving portion arranged beneath the punching means and extending downwardly therefrom, a curved portion extending from the receiving portion, and a delivery portion extending from the curved portion to conduct the punchings upwardly so that a group of them may be removed from the magazine while punchings are being supplied to the magazine, and resilient means holding the magazine and the punching means yieldingly together but permitting relative separation of them when the magazine becomes accidentally jammed by the punchings.

2. The combination of punching means, a magazine to receive punchings formed by the punching means and having an upwardly extending portion from the upper end of which the punchings may be removed, and means to conduct the punchings from beneath the punching means to said upwardly extending portion, a pivoted support to carry said magazine, and a spring to hold said magazine in normal operating position and against the action of which spring the magazine may swing when said magazine becomes accidentally jammed by the punchings.

3. The combination of a die, a punch to cooperate therewith to form punchings from sheet material, means to support said die, a magazine including a downwardly extending portion to which the punchings are delivered from said die, an upwardly extending portion from which the punchings may readily be removed, and a curved portion connecting the downwardly extending portion with the upwardly extending portion, a pivoted support to carry said magazine, a spring to hold the downwardly extending magazine portion against the lower end of the die, and means to align said downwardly extending portion with the die.

4. The combination of a plurality of punch and die sets to form punchings from a strip of material, said sets being arranged one behind another so that all are situated substantially in a plane that extends transversely of the path of strip feeding, (that is, longitudinally of the machine), and magazines one for each punch and die set to receive the punchings, each magazine including a portion as

sociated with one of the dies and extending downwardly therefrom in alignment therewith, an upwardly extending portion, and a curved portion connecting the downwardly extending portion with the upwardly extending portion, the upwardly extending portions being arranged substantially in a plane that extends in the direction of strip feeding, (that is, transversely of the machine) the curved portions being disposed in planes extending angularly from each other in fan-like relation from the downwardly extending portions to the upwardly extending portions.

5. The combination of two rows of punch and die sets to form punchings from a strip of material, the punches of each row being arranged behind each other in a plane transversely of the path of feed of the strip, and magazines, one for each punch and die set, to receive punchings, each magazine including a portion associated with one of the dies and extending downwardly therefrom, an upwardly extending portion and a curved portion connecting the downwardly extending portion with the upwardly extending portion, the downwardly extending portions being arranged in rows under the dies, the upwardly extending portions being arranged in a plane extending at right angles to planes in which the downwardly extending portions are located, and the curved portions being disposed in planes extending angularly from each other in fan-like relation and from the downwardly extending portions to the upwardly extending portions, the curved portions reaching from their rows of downwardly extending portions forwardly and laterally toward opposite sides of the machine.

6. In combination, blank punching means, a magazine for receiving blanks therefrom and means yieldingly supporting the magazine in blank receiving position, whereby provision is made for yielding of the magazine in response to jamming, to avoid breakage.

45. In testimony whereof I have affixed my signature to this specification.

ABRAHAM NOVICK.
